DISPENSING TOP

Woodrow S. Wilson, Altadena, Calif., assignor to Polytop Corporation, Slatersville, R.I., a corporation of Massachusetts

Filed July 22, 1963, Ser. No. 75,898

Term of patent 14 years

(Cl. D58—26)

FIG. 1.

FIG. 2.

FIG. 4.

FIG. 3.

FIG. 5.

FIG. 6.

FIG. 8.

FIG. 10.

FIG. 7.

FIG. 9.

FIG. 11.

FIG. 12.

FIG. 13.

FIG. 14.

FIG. 15.

FIGURE 1 is a front elevational view of a dispensing top showing my new design wherein the top is circular;

FIGURE 2 is a top plan view thereof;

FIGURE 3 is a rear elevation thereof;

FIGURE 4 is a right side elevation thereof;

FIGURE 5 is a left side elevation thereof;

FIGURE 6 is a front elevational view of a dispensing top showing a modified form of my new design wherein the dispensing spout is located on the short axis of an ellipse;

FIGURE 7 is a top plan view thereof;

FIGURE 8 is a right side elevation thereof;

FIGURE 9 is a left side elevation thereof;

FIGURE 10 is a rear elevation thereof;

FIGURE 11 is a front elevational view of a dispensing top showing a modified form of my new design wherein the dispensing spout is located on the long axis of an ellipse;

FIGURE 12 is a right side elevation thereof;

FIGURE 13 is a rear elevation thereof;

FIGURE 14 is a left side elevation thereof; and

FIGURE 15 is a front elevation thereof.

I claim:

The ornamental design for a dispensing top, substantially as shown and described.
